(57) **CLAIM**

The ornamental design for a wearable display device, as shown and described.

DESCRIPTION

FIG. 1 is a front perspective view of a wearable display device according to our design;

FIG. 2 is a front elevation view of the wearable display device of FIG. 1;

FIG. 3 is a back elevation view of the wearable display device of FIG. 1;

FIG. 4 is a right elevation view of the wearable display device of FIG. 1;

FIG. 5 is a left elevation view of the wearable display device of FIG. 1;

FIG. 6 is a top elevation view of the wearable display device of FIG. 1;

FIG. 7 is a bottom elevation view of the wearable display device of FIG. 1; and,

FIG. 8 is a rear perspective view of a wearable display device of FIG. 1.

Broken lines are environmental only and form no part of the claimed design.

Dash-dot lines represent bounds of associated portions of the claimed design and form no part of the claimed design.

Areas of the wearable display device shown with a stipple fill preferably have a color that contrasts with a color of the non-filled areas.
